ATOMIZER CASE

Earl S. Tupper, Upton, Mass.

Application November 26, 1948, Serial No. 62,208

2 Claims. (Cl. 299—89)

1

This invention relates to atomizing containers. It is an object of the present invention to provide an atomizing container which is formed with resilient walls which may be depressed and which will return to their normal shape whereby to effect an atomizing action of the liquid within the container upon an opening being provided in the container through which air may enter and leave the container with the contents thereof and wherein the nozzle is integral with the main portion of the container and wherein the open bottom end of the container is secured and sealed by a cap and a rigid plate therein for maintaining the shape of the bottom of the container and wherein there is a nipple formation on the main container portion which must be severed to permit the atomizing action, but which serves to maintain the contents of the container while the container is in transport from the factory to the purchaser.

Other objects of the present invention are to provide an atomizing container with an integral nozzle or orifice portion which is of simple construction, easy to assemble, inexpensive, easy to prepare for operation, of pleasing appearance, durable and efficient in operation.

For other objects and for a better understanding of the invention, reference may be had to the following detailed description taken in connection with the accompanying drawing, in which:

Fig. 1 is a perspective view of the atomizing container comprising the features of the present invention.

Fig. 2 is an enlarged fragmentary and sectional view taken on line 2—2 of Fig. 1.

Fig. 3 is an enlarged and sectional view of the nozzle portion and taken on line 3—3 of Fig. 2.

Fig. 4 is a transverse sectional view taken on line 4—4 of Fig. 3.

Fig. 5 is an illustrative view showing how the nipple is severed from the upper end of the container to expose the orifice therein.

Fig. 6 is a sectional view, in elevation, taken on line 6—6 of Fig. 1.

Fig. 7 is a perspective view of a concave supporting disk for the bottom end of the container.

Referring now to the figures, 10 represents the main containing portion of the container which is of inverted cup shape and which has a closed and semispherical upper end portion 11 containing a nozzle orifice 12 through which the contents of the container is dispensed. This orifice is provided in enlarged portions of the material as indicated at 13 which has a nipple 14 which must be severed in the manner as shown

in Figure 5 with the knife or other cutting medium 15 in order to adapt the container for use. The enlarged portion 13 supports a bent tube 16 which depends into the bottom of the container in order to extract the liquid contents from the same. Diametrically opposite recesses 17 are provided in the portion 13 by means of which air may traverse the portion 13 to enter the container and provide air pressure on the top of the liquid contents thereof and by which the air can be expelled in order to provide for the atomizing spray of the liquid contents as the container 10 is squeezed. The container 10 is formed of resilient and flexible material in order to resume its shape after squeezing action has been effected. One material which has proven satisfactory is polyethylene, but other materials may be used with good results.

The bottom open end of the container portion 11 is flared outwardly and downwardly as shown at 18 and is adapted to receive a concaved disk 19 serving to support the bottom of the container and to maintain the shape thereof. The disk is held in place by a metallic cap 21 preferably of aluminum and having a similar concaved bottom for receiving the convex side of the disk 19 and a double bent flange 22 adapted to receive the downward portion of 18 and to be extended over the outwardly flanged portion of the container 10 to have clinching engagement with both of said flared portions.

It should be apparent that there has been provided a very simple bottom end construction for this container. The disk will serve to maintain the shape of the bottom of the containing portion 10 and to maintain a sealing engagement of the cap 21 therewith. The container is filled from the bottom and thereafter the disk 19 and the cap 21 are fitted in place. The access to the container thereafter is through the nipple 14 which must be removed to place the container in condition for atomizing action and for the dispensing of the contents thereof.

While various changes may be made in the detail construction, it shall be understood that such changes shall be within the spirit and scope of the present invention as defined by the appended claims.

I claim:

1. An atomizing container comprising a squeezable and resilient containing portion with an integral top having an enlarged depending portion, a tube secured within the depending portion and extending downwardly towards the bottom of the containing portion, the top of the containing por-

tion having a nipple adapted to be severed to expose an orifice extending through the depending portion and in communication with the upper end of the tube, said depending portion having passages by which air when the containing portion has been relieved of the nipple is permitted to enter the containing portion and to permit its exit for atomizing action of the liquid as the containing portion is squeezed, rigid means for closing the bottom of the containing portion, comprising a rigid disc for maintaining the shape of the bottom of the container and a bottom cap for securing the disc in place therewithin, said containing portion being of inverted cup shape, and having an outwardly and downwardly bent flange on its bottom end, said rigid disc extending into the flange to maintain the shape of the bottom of the container and said cap being channeled to receive the downwardly bent part of the flange of the container portion and extending upwardly and outwardly over the top of the flange of the containing portion.

2. An atomizer container, comprising a squeezable and resilient containing portion with an integral top having an enlarged depending portion, a tube secured within the depending portion and extending downwardly towards the bottom of the containing portion, the top of the containing portion having a nipple adapted to be severed to expose an orifice extending through the depending portion and in communication with the upper end of the tube, said depending portion having passages by which air when the containing portion has been relieved of the nipple is permitted to enter the containing portion and to permit its exit for atomizing action of the liquid as the containing portion is squeezed, rigid means for closing the bottom of the containing portion, comprising a rigid disc for maintaining the shape of the bottom of the container and a bottom cap for securing the disc in place therewithin, said

containing portion being of inverted cup shape and having an outwardly and downwardly bent flange on its bottom end, said rigid disc extending into the flange to maintain the shape of the bottom of the container, said rigid disc being concave and dished downwardly at its center, said cap having a disc portion to receive and retain the center of the rigid disc, said cap having a channel rim and an inwardly bent portion extending in clinching engagement with the opposite faces of the downwardly extending part of the flange and the outer face of the outwardly extending part of the flange.
